ROTARY POWER APPARATUS

John F. Skinner, Flint, Mich.

Application January 8, 1940, Serial No. 312,899

2 Claims.

(Cl. 60—54)

This invention relates to rotary power apparatus and particularly to apparatus employing a fluid medium to transmit a torque or rotation from a driving member to a driven member.

The present invention may be considered as an improvement upon the apparatus disclosed in my United States Patent 2,088,818 issued August 3, 1937.

An object of the invention is to adapt the driving member of a power apparatus to rotate within a body of liquid employed to transmit a drive to a driven member, and to provide vanes on the driving member acting to raise said liquid and deliver it to substantially radial nozzles, from which it is expelled centrifugally, at high velocity, against suitable impelling vanes carried by the driven member.

Another object is to adapt the liquid, after expending its centrifugal energy against said vanes to fall back into said tank, so that a limited quantity thereof suffices for continued use of the apparatus.

A further object is to counteract such swirling of the liquid in the tank as would tend to centrifugally resist delivery of the liquid to the nozzle inlets.

A further object is to adapt the driven member of the described apparatus to serve as a cover for the described tank.

These and various other objects the invention attains by the construction hereinafter described and illustrated in the accompanying drawings, wherein:

Fig. 1 is a view in side elevation of an apparatus embodying the invention.

Fig. 2 is a vertical sectional view of the apparatus, taken upon the line 2—2 of Fig. 1.

Fig. 3 is a horizontal sectional view, taken upon the line 3—3 of Fig. 2, showing the nozzle formation of the driving member and the impact-receiving blades of the driven member.

Fig. 4 is a horizontal sectional view taken upon the line 4—4 of Fig. 2, showing the nozzle formation of the driving member, and further showing a set of upper vanes for delivering liquid to the nozzles.

Fig. 5 is a horizontal sectional view taken on the line 5—5 of Fig. 2 showing structural features of the tank, and a set of lower vanes carried by the driving member.

Fig. 6 is a fragmentary vertical section, taken on the line 6—6 of Fig. 2, and showing the inclination of said vanes in the direction of rotation.

Fig. 7 is a sectional detail view, taken on the

line 7—7 of Fig. 1, showing how the tank of the apparatus is anchored to an upright.

In these views, the reference character 1 designates an open-topped circular tank seated on a circular plate 2 which forms the base of the apparatus and is suitably elevated by legs 3. Centrally welded or otherwise rigidly secured to the plate 2, therebeneath, is the housing 4 of an anti-friction thrust bearing 5. Engaging such bearing is the lower end of a substantially vertical shaft 6, upwardly extending along the vertical axis of the tank and projecting a considerable distance above the latter. A bearing 7, journaling the upper end of said shaft is rigidly carried by a plurality of radial arms 8, the outer portions of which are downwardly curved and integrally joined with vertical columns 9, bolted at 10 or otherwise rigidly connected to the plate 2. The upper portion of the tank 1 is rigidly secured to said arms by suitable U-bolts 11, as best appears in Fig. 7.

Welded or otherwise rigidly secured to the shaft 6, within the upper portion of the tank, is the hub 12 of the driving member of a fluid coupling. Rigidly connected, as by welding, to said hub, is a plurality of radially extending vertical plates 13 and to the mid portion of each plate 13 is welded a shorter vertical plate 14 extending outwardly at a gradual convergence to an adjacent plate 13 and forming with the latter a nozzle 15. A top closure for the several nozzles 15 is formed by a horizontal circular plate 16 welded to the top edges of the described vertical plates and extending from the hub 12 to the outer ends of the vertical plates. A bottom closure for said nozzles is formed by a plate 17 of inverted frusto-conical shape, welded to the lower edges of the plates 13 and 14, and extending from the junctures of such plates to their outer ends. Said lower edges are inclined upwardly as they extend outwardly to conform to the inclination of the plate 17. To the inner edge of the plate 17 is welded a depending collar 18, coaxial with the shaft 6 and defining a liquid inlet common to all of the nozzles 15, and said collar has a frusto-conical downward extension 19, providing a flaring entrance to said inlet. Radially disposed within the collar 18 is a plurality of vanes 20 inclined at approximately forty-five degrees to the direction of rotation and serving to impel liquid upwardly into the nozzles when the shaft is driven, and a lesser number of similarly inclined vanes 21 is rigidly carried by and within the extension 19 to apply additional upward impulsion to the liquid.

Spaced slightly above the described driving member of the fluid coupling, is a horizontal circular plate 22 which is centrally apertured to freely accommodate the shaft 6 and which in conjunction with a set of vanes 23 carried by its outer portion, forms the driven member of said fluid coupling. Said outer portion is downwardly curved, as best appears in Fig. 2, to locate the vanes 23 in an outwardly opposed relation to the nozzles 15. Said vanes, which are welded to the plate 22, project toward the nozzles at a predetermined divergence to the latter such that the jets discharged by the nozzles will impose a desired rotative force on the vanes. Welded to the plate 22 thereabove, is a combined hub and pulley element 24, journaled on the shaft 6 through suitable anti-friction bearings 25, said element being formed with a suitable number of grooves 26 engageable by drive belts (not shown) for transmitting any desired drive. The driving member of the fluid coupling provides a support for the driven member thereof, an anti-friction thrust bearing 27 being interposed for that purpose between the plates 22 and 16.

Above the element 24, there is fixedly mounted on the shaft 6 a pulley 28 to which drive is transmitted through a belt 29 from a motor 30 installed on a suitable plate 31 connecting two of the columns 9.

It is preferred to arrange a suitable number of circumferentially spaced, radial vertical plates 32 in the outer portion of the tank 1, extending inwardly from the tank wall, and subjacent to the vanes 23, the utility of these plates being hereinafter explained.

To prevent access of the drive-transmitting liquid to the bearing 5, it is preferred to surround the submerged portion of the shaft 6 with a sealing sleeve 33, welded at its lower end to the tank 1 and having its upper portion overlapped by the lower part of the hub 12, a suitable packing ring 34 being preferably compressed between the top end of said sleeve and an annular shoulder of the hub.

In use of the described apparatus, upon establishing a drive to the shaft 6, the nozzle-forming member is rotated, together with the collar 18, extension 19, and vanes 20 and 21. The latter deliver liquid upwardly and into the nozzles, from which it is continuously centrifugally ejected at high velocity. It will be noted that the nozzles discharge in a direction opposed by a slight angle to the direction of drive, so that inertia of the liquid supplements centrifugal force in imparting an outward velocity. The jets from the nozzles forcefully encounter the vanes 23 and thus transmit a drive to the member 22, 23, and from the latter this drive is transmitted as desired by the pulley element

24. For light loads, the driven member of the fluid coupling will be actuated at a speed only slightly less than that of the driving member, and the transmitted speed will decrease accordingly as the driven load increases. Having spent its velocity against the vanes 23, the drive-transmitting liquid falls back into the outer portion of the tank, maintaining the requisite level in the latter. The purpose of the plates 32 is to prevent such swirling of the liquid as would raise its level adjacent the tank wall and tend to thus cause overflow and withdraw liquid from the vanes 20 and 21.

Any suitable liquid may serve as a power-transmitting medium, water being preferred because of its low cost and ready availability. However, a relatively heavy liquid medium such as mercury may be desirable in case both a maximum power transmission and a minimum size of apparatus are vital.

A drive of the described character presents numerous advantages as compared to ordinary clutches or other positive rotary transmission devices. As above pointed out, an automatic regulation of speed to suit the load is achieved and the power source is safeguarded against overload. Sudden variations of load will not impose undue stresses either on the transmission means or the source of power. Centrifugal force is so utilized in the described apparatus as to assure it a high efficiency. When installed in a vehicle, the apparatus will act strongly to prevent tilting or overturning of such vehicle, due to gyroscopic effect of the rapidly rotating parts.

What I claim is:

1. A rotary power apparatus comprising a tank for receiving a drive-transmitting liquid, a substantially vertical shaft extending through and projecting above said tank, a thrust bearing for said shaft disposed below said tank, a sleeve having liquid-sealed engagement with the tank bottom and extending upwardly above the level of liquid in the tank, in a surrounding relation to said shaft, a driving member secured on said shaft above said sleeve and having a substantially central liquid inlet below the liquid level in the tank, and having a plurality of nozzles discharging toward the wall of the tank, and a driven member rotatable on said shaft above said driving member and having a plurality of vanes opposed to the outlets of said nozzles, and so diverged to the nozzles as to adapt the impact on said vanes of liquid discharged from the nozzles to establish a drive to the driven member.

2. A rotary power apparatus as set forth in claim 1, the driving member having a hub downwardly extending in a surrounding, liquid-sealing relation to the upper portion of said sleeve.

JOHN F. SKINNER.
